US00D613688S

(12) **United States Design Patent**
Yang et al.

(10) **Patent No.:** **US D613,688 S**
(45) **Date of Patent:** **** Apr. 13, 2010**

(54) **BATTERY CONNECTOR**

(75) Inventors: **Chih-Lin Yang**, Tu-Cheng (TW);
Chin-Chou Wang, Tu-Cheng (TW)

(73) Assignee: **Cheung Uei Precision Industry Co., Ltd.**, Tu-Cheng, Taipei Hsien (TW)

(**) Term: **14 Years**

(21) Appl. No.: **29/344,798**

(22) Filed: **Oct. 5, 2009**

(51) **LOC (9) Cl.** **13-03**

(52) **U.S. Cl.** **D13/120**

(58) **Field of Classification Search** D13/118-121,

(57) **CLAIM**

The ornamental design for battery connector, as shown and described.

DESCRIPTION

FIG. 1 is a perspective view of battery connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of battery connector showing our new design.

The broken lines in the Figures are for illustrative purposes and form no part of the claimed designs.

1 Claim, 8 Drawing Sheets

FIG. 1

FIG. 2

FIG. 3

FIG. 4

FIG. 5

FIG. 6

FIG. 7
